PIPE OR CONDUIT BENDERS

Robert Halsey Henderson, East Orange, N. J.

Application October 21, 1955, Serial No. 542,042

4 Claims. (Cl. 153—39)

This invention relates to improvements in pipe or conduit bending tools; and has reference, more particularly, to a novel construction of tool adapted to produce angular bends in pipe, and especially adapted to bend thin wall tubular pipe or conduit.

This invention has for its general object to provide a portable bending tool which can be quickly set up on the job, and which is adapted to produce angular bends in pipe or thin wall electric wire conduit tubing without the formation of kinks or other undesirable distortions, while at the same time providing a tool for such work which enables the user to quickly produce desired bends with a minimum of effort.

The invention has for a further object to provide a pipe or conduit bender comprising a body member or bending saddle having in its top an arcuate channel of semi-circular cross-section of a width corresponding to the external diameter of the pipe or conduit to be bent, the arc of said channel determining the curvature of the bend to be produced, said body member or bending saddle having a transverse abutment spaced outwardly from an end thereof and radially offset from its arcuate channel, whereby to hold or anchor the pipe or conduit subject to bending force applied thereto; and a manipulatable bending jaw for cooperation with the body member or bending saddle, which is adapted to be shifted along the latter to apply progressive or step by step bending force to the pipe or conduit operated upon; said body member or bending saddle and said bending jaw having cooperative means to pivotally engage the latter with the former subject to oscillatory movement toward and from the same; said bending jaw being of relatively short length, and being also provided in its underside with an arcuate channel of semi-circular cross-section and width corresponding to the diameter of the pipe or conduit to be bent, which channel opposes that of the body member or bending saddle, so that, when said bending jaw is closed down upon the body member or bending saddle, the pipe or conduit undergoing bending manipulation will be fully enclosed between these parts at the zone of bend.

Another object of this invention is to provide the body member or bending saddle with means for supporting the same at a place of use, and to provide the bending jaw with means to apply actuating leverage thereto.

The above and other objects will be understood from a reading of the following detailed description of an embodiment of this invention in connection with the accompanying drawings, in which:

Fig. 1 is a side elevational view of a bending tool according to this invention with pipe engaged therewith subject to bending manipulation, and showing the bending jaw as initially disposed to initiate a bending operation; Fig. 2 is a similar view, showing the bending jaw as actuated to effect a first pipe bending step; Fig. 3 is a fragmentary transverse vertical sectional view, taken on line 3—3 in Fig. 2; and Fig. 4 is a view similar to that of Fig. 1, but showing the bending jaw advanced ready to perform a succeeding pipe bending step.

2

Referring to the drawings, in which like characters of reference are employed to indicate corresponding parts, the reference character 10 indicates the body member or bending saddle of the tool, the same having an arcuate

5 top portion 11 along which extends an upwardly or outwardly and endwise open pipe or conduit receiving channel 12. The curvature of the arcuate top portion 11 and the contained channel 12 is of a radius corresponding to the radius of the bend which is to be formed in a pipe or conduit operated upon. Said pipe or conduit receiving channel 12 is of semi-circular cross sectional shape and of a width corresponding to the external diameter of the pipe or conduit to be bent.

Provided in connection with one side of the body 15 member or bending saddle 10, preferably as an integral part thereof, and so as to extend rearwardly from the rear end of the body member or bending saddle, is an arm 13. This arm 13 is provided at its free end with a transverse abutment member 14, which is so spaced 20 away from the rear end of the body member or bending saddle 10 as to form a laterally open gap 15 of sufficient width to permit a pipe or conduit to be entered sidewise therethrough into axially aligned relation to the channel 12 of the body member or bending saddle 10.

25 The underside of the abutment member 14 is provided with a pipe or conduit seating notch 16 disposed in alignment with the channel 12 of the body member or bending saddle, with its open side opposed to and radially offset relative to said channel 12, whereby said notch 30 will seat the upper side of an entered pipe or conduit, when the lower side of said pipe or conduit engages in the rear end of said channel 12 (see Fig. 1).

Intermediate its ends, the body member or bending saddle is provided with a downwardly projecting shank 35 portion 17 for purpose hereinafter set forth. The abutment member 14 is provided with an opening 18 extending longitudinally therethrough, the purpose of which will also be hereinafter explained.

Beginning at points spaced forwardly from the rear end 40 of the body member or bending saddle 10, to extend from said points forwardly along and so as to conformably border opposite sides of the curved top 11 thereof, are laterally projecting track flanges or ledges 19, which are preferably formed as integral parts of the body member 45 or bending saddle.

Provided for cooperation with the body member or bending saddle 10 is a movable bending jaw 20 of longitudinally arcuate formation, and of relatively short length as compared with the length of said body member or bending saddle. The arcuate curvature of said bending jaw corresponds to the curvature of the arcuate top 11 of the body member or bending saddle. Provided in the bottom of the bending jaw 20 is a downwardly and endwise open pipe or conduit embracing channel 21 of semi-circular cross-sectional shape, and of width corresponding to that of the channel 12 of the body member or bending saddle, and therefore likewise corresponding to the external diameter of the pipe or conduit to be bent. Provided at the rear end of the bending jaw, to depend 55 from opposite sides thereof for downward extension across the track flanges or ledges 19 of the body member or bending saddle 10, in straddling relation thereto, are yoke arms 22. Projecting inwardly from the free ends of said yoke arms, to engage the undersides of said track flanges or ledges 19, are rounded pivoting bosses 23, which, in contact with the undersides of said track flanges or ledges, provide a fulcrum about which the bending jaw 20 can be swung relative to the top of the body member or bending saddle 10, when the bending jaw is operatively assembled with the latter. Projecting 60 upwardly from the forward end of the bending jaw is a shank 24 that is adapted to receive application thereto of

70

leverage exerting means for actuating the bending jaw in use.

To support the body member or bending saddle 10 at a place of use, its rear end portion can be secured to a support such as a bench, upright timber, joist or column of a building or any other suitable form of supporting means, by passing a lag screw (not shown) through the opening 18 of the abutment member 14 into such support to anchor the body member or bending saddle thereto for outward projection therefrom, thereby to position the same at a convenient height above the floor of the place of use. To stabilize the thus supported body member or bending saddle against yielding to pipe bending pressure in use, a stay leg 25, preferably comprising a tubular member or section of pipe of inside diameter to telescopically receive said shank portion 17, is applied to said shank portion to incline downwardly and forwardly from the body member or bending saddle to the floor of the place of use, whereby to brace the same against yielding to applied pipe or conduit bending pressure; such method of support being similar to that disclosed in my prior United States Letters Patent No. 1,659,026.

In the use of the bender, a straight length of pipe or conduit P, in which it is desired to form a bend, is passed sidewise through the gap 15, and is then disposed so that its top side seats in the seating notch 16 of the abutment member 14, with the pipe or conduit extending thence through the rear end of the channel 12 of the body member or bending saddle 10, to engage the bottom side of the pipe or conduit therein, with the pipe or conduit thence inclining upwardly and forwardly above said channel 12 (see Fig. 1). The pipe or conduit P being thus initially positioned, the bending jaw 20, which is subject to detachable engagement with the body member or bending saddle 10, is overlaid upon the pipe or conduit P, and initially operatively engaged with the rear end portion of the body member or bending saddle 10 by passing the yoke arms 22 thereof over the latter rearwardly of the extremities of the track flanges or ledges 19, and then shifting the same forward to engage the pivoting bosses 23 beneath the rear end portions of said track flanges or ledges 19, so that the bending jaw 20, as embracing the upwardly and forwardly inclined pipe or conduit P, extends upwardly and forwardly divergent to the underlying body member or bending saddle and its pipe or conduit receiving channel 12 (see Fig. 1). In order to provide sufficient leverage for swinging down the bending jaw 20 with pipe or conduit bending effect, a lever member 26, preferably comprising a suitable length of tubular member or pipe, of inside diameter to telescopically receive the shank 24 of the bending jaw, is applied to said shank. This having been done, the bender is ready to begin the pipe or conduit bending operation.

To start bending manipulation of the pipe or conduit P, the operator grasps the lever member 26 and swings the same downward, thereby swinging downward the bending jaw 20, as fulcrumed by the pivoting bosses 23 against the track flanges or ledges 19 of the body member or bending saddle 10, against the embraced pipe or conduit P. Such down swinging movement of the bending jaw carries the engaged pipe or conduit into the underlying channel 12 of the body member or bending saddle 10, thereby bending said engaged portion of the pipe or conduit conformably to the curvature of the latter. As the bending jaw progressively approaches the body member or bending saddle, the lateral embracing engagement of these parts with the sides of the pipe or conduit constantly increases, thereby increasing the resistance to deforming stresses or strains which, without such lateral support, might well produce undesirable malformation of the pipe or conduit, such as bulges, kinks; the pipe or conduit being fully enclosed by and between the bending jaw and body member or bending saddle when these parts finally meet (see Figs. 2 and 3).

After completion of the above described initial bending operation, if further increase of the angularity of the bend is desired, the bending jaw is up swung and then shifted forwardly along the body member or bending saddle, so as to engage the forwardly extending unbent portion of the pipe or conduit adjacent to the initial bend (see Fig. 4), whereupon the down swinging bending actuation of the bending jaw is repeated. Such step by step bending manipulation can be repeated until a desired angularity of bend is attained.

It will be understood that the channel 12 of the body member or bending saddle and the complementary channel 21 of the bending jaw may be provided in various sizes corresponding to external diameters of different sizes of pipes or conduits, ranging e. g. from $\frac{1}{4}$ to 2 inches in diameter.

Having now described my invention, I claim:

1. A pipe or conduit bender comprising a stationary bending saddle having an arcuate top portion and provided with an upwardly and endwise open pipe or conduit receiving channel extending along said top portion, said channel being of semi-circular cross-section corresponding in width to the diameter of a pipe or conduit to be bent and in depth to the cross-sectional radius of said pipe or conduit, said bending saddle having an arm rearwardly extending from one side thereof, a transverse abutment member supported by said arm in offset relation to the rearward open end of the pipe or conduit receiving channel; said bending saddle having laterally projecting track means bordering the top portion thereof conformably to its curvature, a manipulatable bending jaw opposed to the arcuate top portion of the bending saddle and of substantially less length than said bending saddle, said bending jaw having a bottom curvature corresponding to that of said arcuate top portion of the bending saddle, said bending jaw having in its bottom a downwardly and endwise open pipe or conduit embracing channel corresponding in width to the diameter of the pipe or conduit to be bent and in depth to the cross-sectional radius of said pipe or conduit, and means to detachably pivotally engage the rearward end of said bending jaw with the track means of the bending saddle, said bending jaw and its pivoting means being shiftable along the bending saddle and its track flanges to successive pipe or conduit bending positions.

2. A pipe or conduit bender according to claim 1 wherein the means for pivotally engaging the bending jaw with the bending saddle comprises dependent means laterally offset from the bending jaw at the rearward end thereof and adapted to straddle the track means of the latter, and said dependent means having inwardly projecting pivoting means to engage the undersides of said track means.

3. A pipe or conduit bender comprising a bending saddle having means to support the same, said bending saddle having an arcuate top portion provided with an upwardly and endwise open pipe or conduit receiving channel extending along said top portion, said channel being of semi-circular cross-section corresponding in width to the diameter of a pipe or conduit to be bent and in depth to the cross-sectional radius of said pipe or conduit, said bending saddle having an arm rearwardly extending from one side thereof, a transverse abutment member supported by said arm in offset relation to the rearward open end of the pipe or conduit receiving channel, said bending saddle having laterally projecting track flanges bordering opposite sides of the top portion thereof conformably to its curvature, the rearward ends of said track flanges being spaced a distance forwardly of the rear end of the bending saddle, a manipulatable arcuate bending jaw opposed to the arcuate top portion of the bending saddle and of less length than said saddle, said bending jaw having a bottom curvature corresponding to that of said arcuate top portion of the bending saddle, said bending jaw having in its

bottom a downwardly and endwise open pipe or conduit embracing channel of semi-circular cross-section corresponding in width to the diameter of a pipe or conduit to be bent and in depth to the cross-sectional radius of said pipe or conduit, a lever arm for actuating said bending jaw, and means to detachably pivotally engage the rearward end of said bending jaw with the track flanges of the bending saddle, said means comprising dependent yoke arms respectively laterally offset from opposite sides of the bending jaw at the rearward end thereof and adapted to straddle the track flanges of the bending saddle when moved over the rearward ends of the latter, said yoke arms having inwardly projecting pivoting bosses to engage undersides of the track flanges, said bending jaw and its pivoting means being shiftable along the bending saddle and its track flanges to successive pipe or conduit bending positions.

4. A pipe or conduit bender according to claim 3 where-

in the means for supporting the bending saddle comprises means to secure the same to a stationary support above the floor level at a place of use comprising a fastener receiving opening with which the abutment member of the bending saddle is provided, and a stay leg connected with said bending saddle to extend in downward inclination therefrom to said floor level.
